COINCIDENTAL LOCK

John W. Fitz Gerald, Milwaukee, Wis., assignor to
 Briggs & Stratton Corporation, Milwaukee,
 Wis., a corporation of Delaware

Application June 9, 1939, Serial No. 278,179

13 Claims. (Cl. 70—252)

This invention relates to improvements in automobile locks, and refers particularly to a coincidental lock of the type shown in Patent No. 2,063,088, issued to John W. Fitz Gerald, December 8, 1936.

It is a general object of the present invention to provide a combined steering post and ignition switch lock wherein the locking bolt is retractible to an unlocked position simultaneously with the closing of the ignition switch by key actuated rotation of the lock cylinder and wherein the locking bolt is held in its retracted position as long as the key remains properly within the lock cylinder so that the ignition switch may be turned on and off without causing the bolt to lock the steering column.

More specifically it is an object of this invention to provide a lock of the character described wherein the locking bolt is held in its retracted position until an outward endwise pull is exerted on the key preparatory to removing the same from the cylinder.

Another object of this invention is to provide a lock of the character described wherein this mode of operation is obtained with an exceedingly simple construction which lends itself readily to production methods of manufacture.

In this connection, it is an object of this invention to provide a lock of the character described wherein the bolt is held in its retracted position by a part of the lock cylinder assembly per se so that an outward endwise motion of the lock cylinder produced by an outward pull on the key releases the bolt for spring projection to its operative position.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed in accordance with the best mode so far devised for the practical application of the principles thereof, and in which:

Figure 1 is a top view of a lock constructed in accordance with this invention having parts thereof broken away and in section;

Figure 2 is a cross sectional view taken through Figure 1 on the plane of the line 2—2;

Figure 3 is a sectional view taken through Figure 1 on the plane of the line 3—3;

Figure 4 is an enlarged sectional view taken on the plane of the line 4—4 in Figure 2 and showing the bolt projected to its locked position;

Figure 5 is a view similar to Figure 4 illustrating the bolt retracted and the cylinder and bolt in their positions about to actuate the switch to its closed position;

Figure 6 is a detail view looking up against the bottom of the lock cylinder, its casing, and locking bolt with the cylinder turned to the position at which the ignition switch is off and at which an endwise pull on the key will effect freeing of the bolt, for convenience the bolt being shown in a horizontal position;

Figure 7 is a view similar to Figure 6 but showing the parts in their positions at the instant the bolt is released for operative projection to its locked position;

Figures 8, 9, and 10 are cross sectional views through the lock cylinder taken on the plane of the line 8—8 in Figure 2 and illustrating the cylinder in its different positions of rotation;

Figure 11 is a perspective view of the lock cylinder, its casing, and its end ring disassembled but in their proper order of assembly; and

Figure 12 is a perspective view of the switch parts shown disassembled.

Referring now particularly to the accompanying drawings, in which like numerals indicate like parts, the numeral 5 designates the body of the lock which is preferably a casting having a ring-like portion 6 to embrace a steering column, and a bore 7 for reception of the lock mechanism, indicated generally by the numeral 8.

The ring-like portion 6 is split and has lugs 9 drilled to receive a clamping screw (not shown) by which the ring-like portion may be clamped securely to the steering column. Other lugs 10 or attaching ears provide means for securing the lock body to the dashboard of the automobile to provide support for the steering column.

The bore 7, in which the lock mechanism is mounted, lies in a plane parallel to the axis of the ring-like portion 6 and is intersected by a transverse bore 11 which opens into the interior of the ring-like portion.

A locking bolt 12 is slidably mounted in the bore 11 to have its operative locking end 13 projectable into a recess 14 in the steering column 15, a portion of which is indicated in Figures 3, 4, and 5. A compression spring 16 confined between the closed outer end of the bore 11 and the bottom of a well 17 in the adjacent end of

the locking bolt yieldingly projects the bolt to its operative position engaging the steering column.

The bolt is retractible by means of the lock mechanism upon rotation of its cylinder 18 through the medium of a proper key K, and when retracted to its unlocked position at which rotation of the steering column is unrestrained, the bolt is releasably held by the engagement of a shoulder or abutment 19 thereon with the rear edge of an end ring 20 which forms part of the lock mechanism. This end ring 20 is yieldingly projected toward the bolt for operative coaction with the abutment 19, by a spring 21 encircling the sleeve or casing 22 of the lock mechanism.

The sleeve or casing 22 is secured in the bore 7 by means of a screw 23 threaded into a tapped hole in the body of the lock, with its inner end projecting into a hole 24 in the wall of the casing.

The lock cylinder 18 is of the side-bar locking type in which tumblers 25, indicated in dotted lines in Figure 2, control a locking bar (not shown) which projects from the side of the cylinder into a groove in the sleeve or casing to secure the cylinder against rotation. Insertion of the key K into the cylinder effects retraction of this locking bar and frees the cylinder for rotation in the customary manner.

Rotation of the cylinder is translated into endwise motion of the locking bolt through an eccentric driving cam 26 on the inner end of the cylinder, which projects into a recess 27 in the adjacent side wall of the bolt, the eccentric driving cam engaging one end wall 28 of the recess 27 during retraction of the bolt.

When the cylinder is turned to retract the bolt, the end ring 20, which is nonrotatably but slidably mounted on the sleeve or casing 22, 40 snaps behind the shoulder or abutment 19 to thereafter hold the bolt against projection to its operative position. The shoulder or abutment 19 is formed by leaving a land projecting from a flat surface 29 on one side of the bolt, the flat surface extending from near the inner end of the bolt to the recess 27. One side of this land forms the shoulder 19 and its other side is inclined as at 30 to provide a cam surface which depresses the end ring 20 to allow the land on the bolt to pass and snap behind the shoulder 19.

At its opposite end, the bolt has a similar flat surface 31 to accommodate the diametrically opposite edge of the end ring, as clearly shown 55 in Figure 5.

As noted hereinbefore, the end ring 20 is yieldingly propelled toward the locking bolt so as to actively engage the same and secure it in its unlocked position upon retraction. Such rearward 60 propulsion of the end ring is limited by the engagement of inwardly directed lugs 32 and 33 on the end ring in an annular groove 34 in the inner end of the cylinder. In this manner the spring 21 also acts to oppose outward endwise motion of the lock cylinder. These lugs 32 and 33 are slidably disposed in open slots 35 and 36, respectively, in the inner end of the sleeve or casing 22 whereby the end ring is non-rotatably but slidably connected with the sleeve or casing.

70 The lugs 32 and 33 are engageable in the annular groove 34 of the cylinder through entrance ways 37 and 38, respectively, which lead to the groove from the inner end of the cylinder. These entrance ways are so disposed with relation to 75 each other and the lugs 32 and 33 that assembly

and disassembly of the parts requires a predetermined relative circumferential disposition of the parts, and this relative position lies beyond one of the normal limits of rotation of the cylinder. Consequently, upon assembly of these parts, 5 which as will be readily apparent entails the application of the spring 21 onto the reduced inner end portion 39 of the casing so that it will be confined between the shoulder 40 formed at the juncture of the two diameters of the casing and 10 the forward end of the ring 20, the end ring is securely held in place as long as the cylinder is prevented from being turned to that position of rotation at which assembly and disassembly of the parts is possible.

To define the normal limits of rotation of the cylinder and prevent turning the same to the position at which disassembly of the parts is possible, the inner surface of the cylinder head 41 is of stepped formation to provide two abutments 42 20 and 43 which form the opposite sides of a lug 44. The abutment or stop 42 is engageable with a spring pressed plunger 45 projecting from the end wall of the casing or sleeve 22. Such engagement is effected by counterclockwise rotation 25 of the lock cylinder and defines the extreme limit of counterclockwise movement, at which position the bolt is released and projected to its operative position and the ignition switch is open.

Clockwise rotation of the cylinder to retract 30 the bolt and close the ignition switch is limited by the engagement of the stop abutment 43 with a stop 46, which is formed by one end of a semi-circular counterbore 47 at the mouth of the casing or sleeve. This semi-circular counterbore 47 35 accommodates the lug 44.

In the unlocked position of the cylinder and when the ignition switch is closed, which is the position illustrated in Figure 9, the cylinder is releasably held against accidental rotation by a 40 spring detent comprising the spring pressed plunger 45 and a notch 48 formed in the step 49 on the inner face of the cylinder head.

In turning the cylinder from its unlocked position at which the ignition switch is closed, toward its locked position, which is the only position at which withdrawal and insertion of the key is possible, rotation is interrupted short of its locked position by the engagement of a stop 50 formed by the end of the step 49 with a second 50 spring pressed plunger 51 projecting from the front end of the sleeve or casing. In this position, which is illustrated in Figure 10, the ignition switch is open.

This interruption of rotation produced by the 55 engagement of the stop 50 with the spring pressed plunger 51, however, is not positive for by drawing the cylinder outwardly a distance sufficient to carry the edge of the stop 50 outwardly to the end of the spring pressed plunger, as illustrated in 60 Figure 7, the cylinder is free to turn the additional slight amount necessary to bring it to its fully locked position defined by the engagement of its stop 42 with the spring plunger 45.

Unless it is desired to remove the key, which 65 can be done only in the locked position of rotation of the cylinder and which is accompanied by release of the bolt for projection to its locked position, the cylinder rotation is limited by its stops 43 and 50 engaging the casing stops 46 and 51, respectively, the amount of rotation thus provided being sufficient to allow the ignition switch to be opened and closed.

When it is desired to remove the key and release the bolt, an outward pull is exerted on the 75

key after it has been turned to engage the stops 50 and 51, to carry the cylinder stop 50 past the end of the stop 51, as illustrated in Figure 7. Endwise pull imparted to the key in this manner, 5 is transmitted directly to the end ring 20 to release the bolt by virtue of the engagement of its lugs 32 and 33 with the outer wall of the annular groove 34 in the cylinder.

The ignition switch indicated generally by the 10 numeral 52 is mounted in the bottom of the bore 7 and is actuated by endwise motion of the bolt without, however, projecting its operative end into the bore of the ring-like portion 6. The switch, as best shown in Figure 12, comprises a 15 disc of insulating material 53 seated in the bottom of the bore 7 and carrying two terminals 54 and 55, each of which has a terminal screw 56 projecting through a hole in the closed end of the lock body. The holes in the lock body, 20 through which the screws project, are sufficiently large to provide electrical clearance.

A piece of insulating material 57 bored for the 25 passage of the screws 56 therethrough engages the outer end wall of the lock body to receive the thrust of clamping nuts 58 on the screws.

The terminal 54 is in the form of a flat head flush with the inner surface of the insulating disc 53 while the terminal 55 has a pin 59 projecting therefrom, on which a contactor 60 is pivotally 30 mounted. The contactor comprises a stamping in the form of an elongated plate having spaced arms 61 extending from the opposite side edges thereof and another arm 62 projecting from the outer end thereof. An indentation 63 on the 35 outer end of the arm provides a contact for electrical engagement with the terminal 54 as the arm is swung on its pivoted mounting.

An insulating actuator 64 is embraced by the 40 arms 61 and 62, and a small compression spring 65 is interposed between the actuator and the contactor to provide contact pressure. The actuator is also pivoted on the post 59 and has a lug 66 projecting therefrom for engagement in a transverse recess 67 in the bolt.

45 The relative positions of the recess in the bolt and the mounting for the contactor is such that when the bolt is fully retracted by rotation of the lock cylinder to the limit of its motion defined by the engagement of its stop 43 with the casing stop 46, as illustrated in Figure 9, the ignition switch is closed and the bolt is retracted beyond the position illustrated in Figures 3 and 5.

50 Rotation of the lock cylinder toward its locked position to the point at which the releasable stop effected by the shoulder 50 engaging the spring propelled plunger 51 arrests rotation thereof, carries the switch contactor to its off position while leaving the steering column free for actuation.

55 As pointed out hereinbefore, disassembly and assembly of the cylinder mechanism entails a predetermined relative position of the cylinder with respect to its casing and this position lies beyond one of the normal extreme limits of rotation of the cylinder.

To permit the cylinder to be turned to this position, it is necessary to disengage the spring plunger 45 from the cylinder stop 42 and to effect this result, a hole 68 is formed through the head of the cylinder to align with the spring plunger 45 when the stop 42 is engaged therewith. Thus, by the insertion of a tool through the hole 68, the plunger 45 may be depressed sufficiently to permit the lug 44 to pass the plunger. The cylinder is now free to be turned the additional

amount necessary to effect the desired alignment, which is defined by the engagement of the side 69 of the entrance 38 at the inner end of the lock cylinder with a lug 70 carried by the adjacent portion of the casing.

Spring propelled projection of the locking bolt is limited in the event the locking mechanism is removed, by the inner end of a screw 71 threaded into the lock body with a shoulder 72 formed by one end of a flattened portion 73 in the side 10 of the locking bolt.

From the foregoing description taken in connection with the accompanying drawings, it will be readily apparent to those skilled in the art that this invention provides a coincidental lock 15 of the character described, which is exceptionally practical in construction and in which release of the locking bolt is dependent upon a slight endwise motion imparted to the lock cylinder as an incident to withdrawal of the key, and in which 20 the key cannot be withdrawn without releasing the bolt for projection to its operative position.

What I claim as my invention is:

1. In a lock of the character described: an axially movable spring pressed bolt; an endwise and 25 rotatably movable lock cylinder; means operable by rotation of the lock cylinder for retracting the bolt; and an obstruction positionable to engage and hold the bolt in its retracted position, said obstruction being movable to an inoperative position upon endwise motion of the lock cylinder to free the bolt for spring actuation.

2. In a lock of the character described: a bolt 30 movable endwise to and from a locking position; a spring for yieldingly urging the bolt to its locking position; a lock cylinder; means rotatably and endwise movably mounting the lock cylinder with its axis substantially normal to the axis of the bolt; means operable by rotation of the cylinder for retracting the bolt; and means carried 40 by the lock cylinder and operable in one position of endwise movement of the lock cylinder to engage and hold the bolt in its retracted position.

3. In a lock of the character described: a bolt 45 movable endwise to and from a locking position; a spring yieldingly urging the bolt toward its locking position; a lock cylinder rotatable and endwise movable on an axis substantially normal to the axis of the bolt, said cylinder being rotatable upon the insertion of a proper key, between 50 locked and unlocked positions; means operable upon rotation of the cylinder to unlocked position for retracting the bolt; means on the cylinder yieldingly projected toward the bolt; and a shoulder on the bolt with which said last named 55 means automatically engages upon retraction of the bolt.

4. In a lock of the character described: a locking bolt having a plurality of notches; means mounting the bolt for sliding movement toward 60 and from a locked position; a spring yieldingly urging the bolt to its locked position; and a rotatable and endwise movable member mounted with its axis at an angle to that of the bolt and having a part engageable with one side wall of 65 one of said notches to retract the bolt upon rotation of said member and having another part engageable with one side wall of another notch upon endwise movement of said member toward the bolt to hold the same retracted.

5. In a lock of the character described: a cylindrical bolt having two notches therein; means slidably mounting the bolt for movement to and from a locked position; a spring yieldingly urging the bolt to a locked position; a lock cylinder 75

assembly rotatable and endwise movable on an axis angular to the bolt axis, the inner end of the lock cylinder assembly being engageable in one of the bolt notches upon retraction of the bolt to hold the bolt in retracted position; and means engaging in the other of said bolt notches and driven by rotation of the lock cylinder assembly to retract the bolt.

6. In a lock of the character described: a body having intersecting bores; a bolt slideable in one bore; a spring for yieldingly urging the bolt in one direction; a lock cylinder rotatable and endwise movable in the other bore; means carried by the lock cylinder and operable on the bolt upon rotation of the cylinder for retracting the bolt; and means for moving a part on the lock cylinder into engagement with the bolt upon retraction of the bolt for releasably holding the same in its retracted position.
10. In a lock of the character described: a bolt slideable toward and from a locking position; a spring for yieldingly urging the bolt toward its locking position; a lock cylinder rotatable and endwise movable; means driven by rotation of the cylinder for retracting the bolt; and a latch engageable with the bolt to hold it retracted, said latch being releasable by endwise motion of the cylinder.
15. In a lock of the character described: a bolt slideable toward and from a locking position; a spring for yieldingly urging the bolt toward its locking position; a lock cylinder rotatable and endwise movable; means driven by rotation of the cylinder for retracting the bolt; and a latch engageable with the bolt to hold it retracted, said latch being releasable by endwise motion of the cylinder.
20. In a lock of the character described: a bolt slideable toward and from a locking position; a spring for yieldingly urging the bolt toward its locking position; a lock cylinder rotatable and endwise movable; means driven by rotation of the cylinder for retracting the bolt; and a latch engageable with the bolt to hold it retracted, said latch being releasable by endwise motion of the cylinder.
25. In a lock of the character described: a bolt slideable toward and from a locking position; a spring for yieldingly urging the bolt toward its locking position; a lock cylinder rotatable and endwise movable; means driven by rotation of the cylinder for retracting the bolt; and a latch engageable with the bolt to hold it retracted, said latch being releasable by endwise motion of the cylinder.

30. In a lock of the character described: an axially slideable bolt biased to a locking position; a lock cylinder rotatable and endwise movable on an axis angular to that of the bolt; means yieldingly urging the lock cylinder axially toward the side of the bolt; a shoulder on the side of the bolt engageable by a part on the cylinder when the bolt is in a retracted position; means driven by rotation of the cylinder for retracting the bolt; and means for moving the cylinder part endwise away from the bolt through the application of an outward pull on the cylinder to free the bolt.
35. In a lock of the character described: an axially movable spring pressed bolt; a lock cylinder mounted for rotation on an axis angular to that of the bolt; a driving connection between the cylinder and the bolt whereby rotation of the cylinder retracts the bolt; a latch engageable with the bolt upon retraction to releasably hold the same in its retracted position, said latch being connected with the lock cylinder so as to be disabled by an outward endwise motion of the cylinder; means for defining the extreme locked and unlocked positions of rotation of the lock cylinder; and an intermediate stop for limiting rotation of the lock cylinder toward its locked position.

40. In a lock of the character described: an axially movable spring pressed bolt; a lock cylinder mounted for rotation on an axis angular to that of the bolt; a driving connection between the cylinder and the bolt whereby rotation of the cylinder retracts the bolt; a latch engageable with the bolt upon retraction to releasably hold the same in its retracted position, said latch being connected with the lock cylinder so as to be disabled by an outward endwise motion of the cylinder; means for defining the extreme locked and unlocked positions of rotation of the lock cylinder; and an intermediate stop for limiting rotation of the lock cylinder toward its locked position.
45. In a lock of the character described: an axially movable spring pressed bolt; a lock cylinder mounted for rotation on an axis angular to that of the bolt; a driving connection between the cylinder and the bolt whereby rotation of the cylinder retracts the bolt; a latch engageable with the bolt upon retraction to releasably hold the same in its retracted position, said latch being connected with the lock cylinder so as to be disabled by an outward endwise motion of the cylinder; means for defining the extreme locked and unlocked positions of rotation of the lock cylinder; and an intermediate stop for limiting rotation of the lock cylinder toward its locked position.
50. In a lock of the character described: an axially movable spring pressed bolt; a lock cylinder mounted for rotation on an axis angular to that of the bolt; a driving connection between the cylinder and the bolt whereby rotation of the cylinder retracts the bolt; a latch engageable with the bolt upon retraction to releasably hold the same in its retracted position, said latch being connected with the lock cylinder so as to be disabled by an outward endwise motion of the cylinder; means for defining the extreme locked and unlocked positions of rotation of the lock cylinder; and an intermediate stop for limiting rotation of the lock cylinder toward its locked position.
55. In a lock of the character described: an axially movable spring pressed bolt; a lock cylinder mounted for rotation on an axis angular to that of the bolt; a driving connection between the cylinder and the bolt whereby rotation of the cylinder retracts the bolt; a latch engageable with the bolt upon retraction to releasably hold the same in its retracted position, said latch being connected with the lock cylinder so as to be disabled by an outward endwise motion of the cylinder; means for defining the extreme locked and unlocked positions of rotation of the lock cylinder; and an intermediate stop for limiting rotation of the lock cylinder toward its locked position.

60. In a lock of the character described: a body having intersecting bores; a spring pressed locking bolt slideable in one of said bores; a lock cylinder mounted for axial and rotary motion in the other bore; means for defining locked and unlocked positions of rotation for the lock cylinder; key controlled means for securing the cylinder in its locked position, said means preventing insertion and removal of the key when the cylinder is in any intermediate position; a driving connection between the cylinder and the bolt for retracting the bolt during rotation of the cylinder from locked to unlocked position; a latch engageable with the bolt for releasably holding the same.
65. In a lock of the character described: a body having intersecting bores; a spring pressed locking bolt slideable in one of said bores; a lock cylinder rotatable in said other bore so as to define locked and unlocked positions of rotation for the lock cylinder; key controlled means for securing the cylinder in its locked position, said means preventing insertion and removal of the key when the cylinder is in any intermediate position; a driving connection between the cylinder and the bolt for retracting the bolt during rotation of the cylinder from locked to unlocked position; a latch engageable with the bolt for releasably holding the same.
70. In a lock of the character described: a body having intersecting bores; a spring pressed locking bolt slideable in one of said bores; a lock cylinder rotatable in said other bore so as to define locked and unlocked positions of rotation for the lock cylinder; key controlled means for securing the cylinder in its locked position, said means preventing insertion and removal of the key when the cylinder is in any intermediate position; a driving connection between the cylinder and the bolt for retracting the bolt during rotation of the cylinder from locked to unlocked position; a latch engageable with the bolt for releasably holding the same.

retracted, said latch being connected with the lock cylinder so that outward endwise motion of the cylinder releases the latch and frees the bolt; and an intermediate stop for limiting rotation of the cylinder towards its locked position at an intermediate position at which withdrawal of its key is impossible, said intermediate stop being disabled by an endwise pull on the lock cylinder which also releases the latch so that the normal pull on the key to withdraw the same imparts endwise motion to the cylinder and releases the latch.

10. In a coincidental lock of the type adapted to be mounted on the steering column of an automobile and having a bolt engageable with a recess in the column to secure the same against rotation and a switch for controlling the ignition of the automobile the combination of: a lock body having intersecting bores in one of which the bolt is slideable; a lock cylinder rotatable in the other bore; a driving connection between the cylinder and the bolt whereby rotation of the cylinder is translated into endwise motion of the bolt; a pivoted contactor for the ignition switch; and means connecting the contactor with the bolt so that sliding motion of the bolt swings the contactor on its pivot to open and close the switch.

15. In a coincidental lock: a body having intersecting bores; a spring pressed locking bolt slideable in one bore with a part thereof in the other bore; a lock cylinder rotatable and endwise movable in said other bore; a driving connection between the cylinder and the locking bolt whereby rotation of the cylinder in one direction slides the bolt to an unlocked position and rotation in the opposite direction permits the bolt to be spring propelled toward its locked position; a latch for limiting motion of the locking bolt in an intermediate position and releasably restraining the locking bolt from movement to its locked position while permitting a substantial degree of sliding motion of the bolt toward and from its unlocked position, said latch being connected with the lock cylinder in a manner such that an outward endwise motion of the cylinder releases the latch; an electric switch carried by the body and having a movable contactor adjacent to the locking bolt; and a driving connection between the locking bolt and the contactor whereby sliding motion of the bolt between its unlocked position and said intermediate position carries the contactor to and from a switch closing position.

20. In a coincidental lock of the type adapted to be mounted on the steering column of an automobile and having a bolt engageable with a recess in the column to secure the same against rotation; a lock body having two bores one of which communicates with the other at a medial portion thereof and in which the bolt is slidably received to lie crosswise of said other bore; a lock cylinder rotatable in said other bore at one side of the bolt; a driving connection between the cylinder and the bolt at said side of the bolt whereby rotation of the cylinder is translated into endwise motion of the bolt; switch mechanism in said other bore at the opposite side of the bolt including a pivoted contactor for the switch; and means at said opposite side of the bolt connecting the contactor with the bolt so that sliding motion of the bolt swings the contactor on its pivot to open and close the switch.

JOHN W. FITZ GERALD.
